TOILET FLUSHING APPARATUS

Thomas J. Dunn, Laurinburg, N. C., assignor of
one-half to Lonnie Hammond, Laurinburg,
N. C.

Application October 23, 1939, Serial No. 300,793

7 Claims.

(Cl. 4—40)

This invention relates to a toilet apparatus and more especially to a means for flushing toilet devices such as commodes and urinals. It is a well known fact that the average toilet now in use creates much objectionable noise while it is being flushed, which continues until the tank from which the water flows fills up again to original height. This noise is partially due to the manner in which the water is introduced into the bowl and also partially due to the actuation of the valve which allows the water to again refill the toilet tank.

It is, therefore, an object of this invention to provide a toilet flushing apparatus which will serve to minimize the noise which is created by the emptying and filling of the water closet as a result of a flushing operation. Broadly speaking, the invention comprises the combination of a bowl, a source of water under pressure and a tank disposed intermediate the source of water and the bowl into which the water is allowed to accumulate or enter prior to introducing it into the bowl. This intermediate chamber is so arranged that the water after entering is not under pressure, but when the toilet is flushed it is allowed to move by gravity into the toilet bowl.

It is a further object of this invention to provide a toilet apparatus of the class described with a novel apparatus for creating a secondary flush in the toilet bowl so that the gases from the sewage pipe will not be allowed to move upwardly into the room while the toilet bowl is being refilled to the normal water level after the flush has been completed.

Some of the objects of the invention having been stated, other objects will appear as the description proceeds when taken in connection with the accompanying drawings, in which—

Figure 1 is a front view of a toilet showing certain portions thereof in section and illustrating my invention;

Figure 2 is a view looking at the left hand side of Figure 1, showing the toilet bowl in section;

Figure 3 is a vertical sectional view looking from the front side of the toilet showing a slightly modified form of the invention.

Referring more specifically to the drawings, the numeral 10 denotes a conventional toilet bowl having a seat 11 pivoted to the upper side thereof as at 12. This toilet has an inlet opening 14 and an outlet opening 15 and when the water is introduced into the bowl it is expelled by well known syphon principles through the outlet.

Communicating with the inlet opening 14 is an opening 16 in the lower portion of a tank 17,

said tank 17 having upper and lower compartments 18 and 19 respectively therein. These compartments are separated by a partition 20. The upper portion of the compartment 18 has an opening 25 which is normally closed by plate 26 which is secured to the upper side of the tank 17 by any suitable means such as stud bolts 27. The plate 26 has a centrally disposed port 29 therein which is normally closed by a valve 30. The bolts 27 are also adapted to hold a dome-shaped member 32 which encases the valve 30 and the opening 29. This dome-shaped member has an inlet pipe 33 which serves to introduce a supply of water under pressure therein. Normally the pressure of the water within this member 32 serves to keep the valve 30 tightly seated in the port 29.

The valve 30 is secured to the upper end of a vertically disposed rod 35, said rod having its intermediate portion slidably mounted in the central portion of partition 20. The lower end of the rod 35 has a pin 36 disposed therein which pin also penetrates suitable slots 37 in horizontally disposed lever 38. Lever 38 is pivoted as at 39 intermediate its ends to a bracket 40 extending from the interior sidewall of the lower compartment 19.

The other end of the lever 38 projects laterally through a slot 41 in the sidewall of the tank and extends a substantial distance beyond the exterior thereof so that one may engage this lever when it is desired to flush the toilet. When it is desired to admit water into the compartment 18 the lever 38 is rotated in a counterclockwise manner in Figure 1 which will raise the valve 30 off of the opening 29 to allow the water within the dome 32 to enter the chamber 18.

It is very essential that the closing of the valve 30 be somewhat delayed, therefore, a suitable dash pot 44 is provided, said dash pot being pivoted as at 45 to the lower portion of the partition 20. This dash pot has a piston 46 slidably mounted therein which is connected by way of a piston rod 47, at a point such as 49 on lever 38. This dash pot has a spring-pressed intake valve 50 in the upper end thereof and a very small port 51 in the upper side. Both the valve 50 and the port 51 are disposed at a point above the piston 46. When the lever 38 is rotated in a counterclockwise manner in Figure 1 the valve 50 will automatically open to allow air to freely enter above the piston so that practically no resistance will be offered by the dashpot to the counterclockwise rotation of this lever. On the other hand, when the toilet has been flushed and the

water pressure within the dome 32 tends to close the opening 29, the lever 28 will be rotated in a clockwise direction and at this time the valve 50 will close so as to allow no air to escape at this point; consequently, all the air that escapes will have to pass through the small port 51. As this port is very small, the air will escape comparatively slowly, and the closing of the valve 30 to the position as shown in Figure 1 will be somewhat delayed. This will provide sufficient time for the water under pressure to enter the chamber 18 for toilet flushing purposes.

The return of the valve 30 to normal position is also somewhat delayed by a bell shaped member 55 which is secured to the rod 35 as at 56. Upon the raising of the rod 35 and the valve 30, during a flushing operation the bell-shaped apparatus is likewise raised, and when the water escapes into the chamber 18, air will be trapped in the upper interior portion of the member 55, which will serve to buoy this member upwardly. The member 55 returns to the seated position after the water in compartment 18 escapes and then the water within member 55 is allowed to escape into the compartment 18 by way of notches 57 in the lower rim of the bell.

Another function of this bell shaped member 55 is to prevent water from escaping from chamber 18 into the compartment 19 therebelow at a point where the rod 35 is slidably mounted in partition 20. It will be noted that a sleeve 21 serves to slidably confine the rod 35 in an upright position. By having this bell-shaped member the air trapped within the upper portion thereof during a flushing operation will serve to prevent water from rising above the top of the sleeve 21; consequently water cannot escape from chamber 18 into chamber 19, except through pipes to be later described.

Also it is necessary to provide some means to allow the air, which is displaced by the water coming from dome-shaped member 32 into the compartment 18, to escape. In order to make this provision the rod 35 has a vertically disposed bore 58 in the intermediate portion thereof, said bore having a horizontal bore 59 communicating therewith and also with compartment 18. The lower end of the bore 58 has a second horizontally disposed bore 60 which allows the air within the bore 58 to escape into compartment 19. Consequently as the water enters and displaces the air in the upper compartment 18, this air will be allowed to escape into compartment 19 by way of bores 59, 58 and 60.

After the water comes into the upper compartment 18 it is allowed to escape therefrom into the bowl by means of gravity. The means for conducting this water into the bowl comprises a pair of L-shaped pipes 62 the intermediate portions thereof being mounted in the partition 20. The upper ends of these pipes have large horizontal bores 63 therein as well as smaller bores 64 and 65. These bores allow the water within the compartment 18 to enter the pipes 62. The lower ends of the pipes 62 are connected by means of a union 66 to a T-shaped pipe 67, the lower end of the T-shaped pipe being adapted to penetrate the opening 16 in the lower portion of the tank 17 as well as the inlet opening 14 of the bowl. It is seen that after the water is released from the dome 32 into the chamber 18 that the flow therefrom into the bowl will be at its maximum when the water level is highest. As the water level lowers beneath holes 65, then holes 64 and finally holes 63, the flow of the water will gradually decrease.

These holes 64 and 65 provide a secondary flush which serves to keep water in the bowl during the flushing operation and thereby prevent sewer pipe gases from escaping into the toilet room.

Figure 3 shows a slightly modified form of the invention in which the dome shaped member 32 in the preceding form is omitted. Instead, a diaphragm flush valve is substituted. A pipe 68 leads to the intake chamber 69 of the valve casing 70. This pipe is adapted to have water under pressure therein. Disposed within the casing 70 is a main valve seat 71 which seat is secured on the upper end of a sleeve guide 72. This guide is mounted for vertical sliding movement within and concentric with the surrounding pipe 73. The valve seat 71 normally rests on the upper rim of the pipe 73. Secured to the upper end of sleeve 72 and above the valve seat 71 is a leather cup washer 74, the downturned rim of which is adapted to expand against the interior of bore 75 within an inverted metallic cup member 76, said member 76 being held in a stationary position within the casing 70. Under normal conditions the water pressure enters from pipe 68 into compartment 69 from whence it flows upwardly through a small bore 77 and into chamber 75. This pressure in chamber 75 on the top of the valve seat 71 and the cup washer 74 tends to push these members downwardly to cause the valve seat to fit on top of the upper rim of pipe 73 and thereby prevent any water from escaping from compartment 75 into the pipe 73. It will be noted however that the guide sleeve 72 has a bore 78 in the upper end thereof which is normally closed by a valve 79, said valve having a stem 80 extending downwardly therefrom, the lower end of which is disposed in close proximity to a horizontally slidably mounted pin 81. This pin is normally pressed to the left against the right hand end of an operating handle 82 by means of a suitable compressed spring 83. Since the left-hand end of the pin 81 engages the center of the right hand end of the operating handle, it is evident that when the free end of this handle is rotated in any direction the pin 81 will be pushed to the right against the lower end of valve stem 80. When this is done the water which is stored under pressure within the compartment 75 will be allowed to flow downwardly and escape through the opening 78 from whence it will flow into a pipe 85. Upon the release of the water from the compartment 75, the pressure within the chamber 69 will be greater than the pressure within the compartment 75; consequently, the sleeve 72 together with the cup-shaped member 73 will move upwardly and at the same time unseat the valve 71 to allow the water to flow in a comparatively large stream 69 over the upper rim of pipe 73 and then downwardly into pipe 85.

The pipe 85 extends downwardly and into a tank 86. The lower end of the pipe 85 is curved to a substantially horizontal position as at 85a and it will be noted that the curved portion is located only a slight distance above the bottom of a partition 87 within the tank. The lower portion of the tank rests upon a horizontally disposed plate 88 which, in turn, is mounted on the top of bowl 19 previously described. This plate has an opening 89 in the central portion thereof which communicates with the opening 14 in the bowl. When the water is released from the pressure pipe 67 through the above described valve mechanism into the upper compartment 69, it is allowed to escape therefrom by way of gravity 75

into the bowl 10 in a manner similar to that in the preceding form.

It is seen that the partition 87 within the tank 86 has a pair of pipes 91 extending upwardly therefrom, said pipes having holes 92, 93 and 94 therein which serve as escape ports through which the water is allowed to pass from the compartment 90. These holes are progressively smaller, the larger being 92 and the smaller being 94. The lower ends of pipe 91 are connected to T-member 95 the lower end of said member is disposed in the opening 14.

In order to provide means for the air to escape upon the filling of the compartment 90 with water, a pipe vent 97 is provided the upper end of which is disposed in close proximity to the top of compartment 90 and the lower end penetrating the partition 87. This pipe will allow the air to escape or to enter as the water is entering or leaving the compartment 90. This tank 86 is also provided with a door 98 which is secured to the upper side of the tank by any suitable means such as stud bolts 99. This door may be removed when it is desired to inspect the interior or compartment 90.

In the drawings and specification there has been set forth a preferred embodiment of the invention and although specific terms have been employed they are used in a generic and descriptive sense only and not for purposes of limitation, the scope of the invention being set forth in the appended claims.

I claim:

1. Toilet flushing apparatus comprising a tank, a pipe penetrating the tank and having a plurality of ports therein at different levels, means for admitting a predetermined quantity of water to the tank to flow through said ports to flush the toilet.

2. Apparatus for flushing a toilet bowl comprising a water tank, a pipe establishing communication between the tank and the bowl, said pipe having a plurality of holes therein disposed at different levels in the tank, means for admitting a volume of water to the tank at a rate of flow which is in excess of the rate of flow through said holes.

3. Toilet flushing apparatus comprising a tank, a pipe penetrating the tank and having a plurality of ports therein at different levels, means

for admitting a predetermined quantity of water to the tank to flow through said ports to flush the toilet, the size of the ports diminishing from the highest level to the lowest level.

4. Apparatus for flushing a toilet bowl comprising a water tank, a pipe establishing communication between the tank and the bowl, said pipe having a plurality of holes therein disposed at different levels in the tank, means for admitting a volume of water to the tank at a rate of flow which is in excess of the rate of flow through said holes, the size of the holes in said pipe diminishing from the highest level to the lowermost level.

5. Apparatus for supplying water to a toilet bowl to flush the same comprising a tank, a discharge pipe leading from the tank into the bowl, means for storing a body of water at a point removed from the tank, means for admitting the stored water to the tank, and means associated with the discharge pipe for gradually diminishing the rate of flow of water from the tank to the bowl after the stored water has been admitted to the tank.

6. Apparatus for supplying flushing water to a toilet bowl comprising a tank, a discharge pipe leading from the tank to the bowl, the upper portion of the discharge pipe extending a substantial distance and having a plurality of ports therein, the ports increasing in size in direct proportion to their distance from the bottom of the tank, and means for admitting water to the tank at a rate greater than the rate of overflow.

7. Apparatus for supplying flushing water to a toilet bowl comprising a tank, a discharge pipe leading from the tank to the bowl, the upper portion of the discharge pipe extending a substantial distance above the bottom of the tank and having a plurality of ports therein, the ports increasing in size in direct proportion to their distance from the bottom of the tank, a storage compartment for water disposed above the tank, a valve in the storage compartment for establishing communication between the compartment and the tank, means penetrating the tank and connected to the valve for opening the valve to allow the water in the storage compartment to flow into the tank.

THOMAS J. DUNN. 50
